ROTARY DRILL FOR DRILLING WELLS

Filed April 6, 1948

UNITED STATES PATENT OFFICE

2,611,583

ROTARY DRILL FOR DRILLING WELLS

William H. Ellis, Lovelaceville, Ky.

Application April 6, 1948, Serial No. 19,233

2 Claims. (Cl. 255—23)

1

My invention relates to rotary drills for drilling wells and an object of my invention is to provide a drill of the character indicated above, wherein the bit is removably secured to the lower end of the well casing, which serves also as a drill stem.

Another object of my invention is to provide a drill of the character indicated above, the well casing of which is equipped with an outer casing adapted to be rotated about the axis of the well casing, and with adjustable means for releasably connecting the two casings with each other, so that the well casing is adapted to be driven by the outer casing.

A further object of my invention is to provide a drill of the character indicated above, in which the outer casing and the means for connecting the two casings with each other are adapted to be removed when the drilling operation is completed.

Other objects of my invention not specifically mentioned may appear in the following specification describing my invention with reference to the accompanying drawing illustrating a preferred embodiment of my invention. It is, however, to be understood that my invention is not to be limited or restricted to the exact construction and combination of parts described in the specification and shown in the drawing, but that such changes and modifications may be made which fall within the scope of the claims appended hereto.

In order that my invention may be better understood, I will now proceed to describe it with reference to the accompanying drawing, in the several figures of which similar parts are indicated by similar reference characters and where-

in:

Figure 1 is an elevational front view partly shown in section of a rotary drill according to my invention;

Figure 2 is a sectional view taken on line 2—2 in Figure 1, the gear housing cover being omitted;

Figure 3 is a vertical sectional view taken through the gear housing of the rotary drill of my invention;

Figure 4 is a sectional view taken on line 4—4 in Figure 1 and showing a top plan view of a pipe wrench used in connection with the drill of my invention; and

Figure 5 is a sectional view taken on line 5—5 in Figure 1.

The rotary drill forming the subject matter of my invention comprises a substantially circular body 10, on one side of which a radially extending flat arm 11 is formed, on the top of which a bearing 12 is formed adjacent its outer edge. On the lower surface of the arm 11, a downwardly extending longitudinal central rib 13 is provided and on each side of this rib a supporting angle 14 is secured by means of bolts 15 or the like extending through the upstanding legs of the angles 16 and through the rib. Diametrically opposite of the rib 13, a narrow rib-like projection 16 extends radially outward from the body 10 and a second pair of supporting angles 17 is secured to this projection by means of bolts 18 or the like. The four supporting angles 14 and 17 are arranged so that the lower surfaces of the outwardly extending legs thereof are located substantially in the same horizontal plane. Each of said outstanding angle legs is provided with a plurality of bolt holes 19.

The body 10 is provided with a centrally located bore 20 having counterbore 21 at its upper end. A bushing 22 is arranged in the bore 20 and has on its upper end a circumferential flange 23 fitting snugly in the counterbore 21. A bowl shaped gear housing 24 has a central circular opening 25 surrounded by an upwardly extending sleeve 26 and rigidly mounted on top of the body 10 as indicated at 26a by welding.

The inner diameters of the bushing 22 and of the sleeve 26 are equal, and these two elements are arranged to form a bearing for an outer casing C consisting in a pipe 27 located rotatably in the bushing and the sleeve and extending upwardly somewhat above the upper edge of the gear housing 24 and downwardly a comparatively long distance below the lower surface of the horizontal legs of the support angles 14 and 17. Approximately one half of the circumferential wall of nearly the entire outer casing portion projecting below the angles is cut away to form an elongated open slot 28 for a purpose to be described later. A bevel gear 29 encircles the upper portion 30 of the outer casing pipe 27 to which it is secured as at 29a, by welding and rests rotatably on the upper edge of the sleeve 26.

A shaft 30 is rotatably supported in the bearing 12 and extends rotatably through a bushing 31 driven into a hole 32 in the outer wall of the gear housing 24. On the inner end portion of the shaft 30 a bevel pinion 33 is rigidly mounted and meshes with the bevel gear 29. On the outer end of the shaft 30 a pulley 34 or the like, is rigidly mounted and is adapted to be driven by some conventional means (not shown). The gear housing may contain a lubricating means such as oil, as indicated at 35, so that the pinion 33 dips into it and the gears are oiled all the time. A cover 36 is removably secured onto the gear housing 24 by means of a plurality of screws 37 or the like. The outer casing pipe 27 extends through said cover and a packing 38 is provided between the casing pipe and the cover.

A well casing 39 extends freely through the outer casing 27 and is constructed in the conventional manner. On the lowermost end portion of the well casing a conventional drive shoe 40 is securely mounted and a clay bit 41 made from a flat piece of tool steel is set into diametrically

extending slots provided in the bottom edge of the drive shoe.

A pipe wrench W consists of a flat body 42 on the foremost end portion of which a pipe wrench chain 43 is pivotally mounted as indicated at 44. The body portion adjacent this pivot connection is provided with a plurality of gripping teeth 45 projecting upwardly in respect to said body and radially toward each other. On the last free link of the pipe wrench chain 43 an eye bolt 46 is pivotally mounted. A longitudinal slot 47 is provided in the body 42, and the bolt 46 extends through said slot. The pipe wrench W is arranged on the well casing 39 so that the gripping teeth 45 engage said casing and the pipe wrench chain 43 surrounds it. On the end of the body opposite to the chain connection 44 a handle 48 is formed. When the wrench is put in position on the well casing a nut 49 or the like is mounted on the portion of the bolt 46 extending through the slot 47. A hand lever 50 is pivotally mounted on the nut, so that the nut can be tightened by means of said hand lever. The nut engages the body 42 and tightens the grip of the wrench chain 43 on the well casing. The hand lever 50 is pivoted to extend downwardly. The handle 48 is located adjacent the edge of the slot in the outer casing 27 as shown at 51. When the shaft 30 is rotated, the outer casing will be rotated about its axis and the handle is engaged by the slot edge, so that the well casing 39 is also rotated about its axis. The drill bit 41 drills into the clay or dirt. The well casing slides downwardly with respect to the outer casing. When the pipe wrench handle 48 arrives at the lower end of the outer casing, the chain 43 is loosened and the pipe wrench is slid upwardly on the well casing and then the chain is tightened again. This operation is repeated, until the well is completed. Then the pipe wrench W is removed from the well casing and the outer casing is lifted from its seat on the gear housing after the cover has been removed.

The above described drill may be mounted on a pair of skids 51 or the like, which are adapted to be secured to a motor truck (not shown) or the like. The support angles 14 and 11 are secured onto these skids by bolts extending through the holes 14 and 19 in said angles respectively.

For maintaining the well pipe or casing 39 centered within the outer case C any suitable means may be employed such, for example, as the collar 39a inserted into the top end of the outer casing C.

In a drill rig of the character herein described the casing or pipe 39 is rotated at about 100 revolutions per minute which causes the clay drill 41 to bore into the earth. During this boring water is pumped down through the casing or pipe 39 to keep the bit cleaned out, the water flowing back up the hole around the casing or pipe 39 and out of the outer casing C through the opened lower part thereof. The water returning from the drill hole may be collected in any suitable hole or basing adjacent to the well and used over again.

As is common practice in drilling wells in this manner, the shoe 40 in which the bit 41 is held, is provided with suitable water outlet apertures 40a through which the wash water passes from the casing 39.

The bit 41 is secured in the slot in the lower part of the shoe 40 by a soft bronze weld on one side only of the bit which permits the bit to be

knocked out when the well is completed, the bit being left in the well.

I claim:

- 5 1. A rotary drill for drilling wells comprising an outer casing, means supporting the same vertically for rotation, a well pipe extending through the outer casing and supported for rotation therein, a drill bit mounted on the lower end of the well pipe, means for releasably and slidably connecting the casing and pipe with each other, means for rotating said outer casing, the means for rotatably supporting the outer casing including a bowl like gear housing provided with a central opening in its bottom and an upwardly 15 extending sleeve defining said opening and adapted to receive the outer casing rotatably therein, a fixed body provided with a vertical bore having a counterbore at its upper end, a bushing having the same inside diameter as the sleeve and fitting snugly into the bore, a flange on the upper end of the bushing fitting snugly into the counterbore, the gear housing being rigidly mounted on top of the body so that the sleeve and the bushing are arranged coaxially with each 20 other, a bevel gear rigidly mounted on the upper portion of the outer casing within the gear housing and rotatably resting on the upper edge of the sleeve, a horizontal bearing formed on the body, a shaft rotatably mounted in said bearing, means 25 for applying rotary power to the shaft, the inner end portion of the shaft projecting rotatably through the wall of the gear housing, and a bevel pinion rigidly mounted on said inner end portion of the shaft and meshing with the bevel gear.
- 30 2. A rotary drill for drilling wells comprising an outer casing, means supporting the same vertically for rotation, a well pipe extending through the outer casing and supported for rotation therein, a drill bit mounted on the lower end of the well pipe, means for releasably and slidably connecting the casing and pipe with each other, means for rotating said outer casing, the means for rotatably supporting the outer casing including a bowl like gear housing provided with a central opening in its bottom and an upwardly 35 extending sleeve defining said opening and adapted to receive the outer casing rotatably therein, a fixed body provided with a vertical bore having a counterbore at its upper end, a bushing having the same inside diameter as the sleeve and fitting snugly into the bore, a flange on the upper end of the bushing fitting snugly into the counterbore, the gear housing being rigidly mounted on top of the body so that the sleeve and the bushing are arranged coaxially with each other, and a plurality of support-angles secured to the body and adapted to be secured to a ground traversing supporting structure.
- 40 3. A rotary drill for drilling wells comprising an outer casing, means supporting the same vertically for rotation, a well pipe extending through the outer casing and supported for rotation therein, a drill bit mounted on the lower end of the well pipe, means for releasably and slidably connecting the casing and pipe with each other, means for rotating said outer casing, the means for rotatably supporting the outer casing including a bowl like gear housing provided with a central opening in its bottom and an upwardly 45 extending sleeve defining said opening and adapted to receive the outer casing rotatably therein, a fixed body provided with a vertical bore having a counterbore at its upper end, a bushing having the same inside diameter as the sleeve and fitting snugly into the bore, a flange on the upper end of the bushing fitting snugly into the counterbore, the gear housing being rigidly mounted on top of the body so that the sleeve and the bushing are arranged coaxially with each other, and a plurality of support-angles secured to the body and adapted to be secured to a ground traversing supporting structure.
- 50 4. A rotary drill for drilling wells comprising an outer casing, means supporting the same vertically for rotation, a well pipe extending through the outer casing and supported for rotation therein, a drill bit mounted on the lower end of the well pipe, means for releasably and slidably connecting the casing and pipe with each other, means for rotating said outer casing, the means for rotatably supporting the outer casing including a bowl like gear housing provided with a central opening in its bottom and an upwardly 55 extending sleeve defining said opening and adapted to receive the outer casing rotatably therein, a fixed body provided with a vertical bore having a counterbore at its upper end, a bushing having the same inside diameter as the sleeve and fitting snugly into the bore, a flange on the upper end of the bushing fitting snugly into the counterbore, the gear housing being rigidly mounted on top of the body so that the sleeve and the bushing are arranged coaxially with each other, and a plurality of support-angles secured to the body and adapted to be secured to a ground traversing supporting structure.
- 60 5. A rotary drill for drilling wells comprising an outer casing, means supporting the same vertically for rotation, a well pipe extending through the outer casing and supported for rotation therein, a drill bit mounted on the lower end of the well pipe, means for releasably and slidably connecting the casing and pipe with each other, means for rotating said outer casing, the means for rotatably supporting the outer casing including a bowl like gear housing provided with a central opening in its bottom and an upwardly 65 extending sleeve defining said opening and adapted to receive the outer casing rotatably therein, a fixed body provided with a vertical bore having a counterbore at its upper end, a bushing having the same inside diameter as the sleeve and fitting snugly into the bore, a flange on the upper end of the bushing fitting snugly into the counterbore, the gear housing being rigidly mounted on top of the body so that the sleeve and the bushing are arranged coaxially with each other, and a plurality of support-angles secured to the body and adapted to be secured to a ground traversing supporting structure.
